US0D1107211S

(12) **United States Design Patent** (10) **Patent No.:** **US D1,107,211 S**
(45) **Date of Patent:** **** Dec. 23, 2025**

(54) **FAN**

(71) Applicant: **SHENZHEN CARTER TECHNOLOGY CO., LTD.,**
Guangdong (CN)

(72) Inventor: **Xuan Lin**, Guangdong (CN)

(73) Assignee: **SHENZHEN CARTER TECHNOLOGY CO., LTD.,** Shenzhen (CN)

(**) Term: **15 Years**

(21) Appl. No.: **29/974,172**

(22) Filed: **Nov. 20, 2024**

(51) LOC (15) Cl. **23-04**

(52) U.S. Cl. **USPC D23/380**

(58) **Field of Classification Search**

USPC D23/370, 380-382, 411-412
CPC F04D 25/08; F04D 25/084; F21V 33/00;
F21V 33/0096

(57) **CLAIM**

The ornamental design for a fan as shown and described.

DESCRIPTION

FIG. 1 is a perspective view of a fan showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the fan that form no part of the claimed design.
